UNITED STATES PATENT OFFICE.

FRANK R. DRAVO, OF SEWICKLEY, PENNSYLVANIA, ASSIGNOR TO THE DRAVO CONTRACTING COMPANY, OF PITTSBURGH, PENNSYLVANIA, A CORPORATION OF PENNSYLVANIA.

DRIVING GEAR FOR BOATS.

Application filed March 21, 1925. Serial No. 17,222.

To all whom it may concern:

Be it known that I, FRANK R. DRAVO, a citizen of the United States, residing at Sewickley, county of Allegheny, and State of Pennsylvania, have invented a new and useful Improvement in Driving Gears for Boats, of which the following is a full, clear, and exact description.

The present invention relates to means for transmitting the drive from a power unit to the paddle wheel shaft of a boat having the paddle wheel located at the stern.

It is customary at the present time in tow boat construction to locate a paddle wheel at the stern of the boat and drive the same by means of a power unit, such as a motor, located at a convenient point in the boat. The drive is transmitted from the motor to the paddle wheel shaft through driving connections comprising a cross shaft and means located at the sides of the boat and operatively connecting the corresponding ends of the paddle wheel shaft and cross shaft, which means may either be gearing or sprocket chains engaging driving sprockets on the ends of the shafts. With either form of drive, it has heretofore been practically impossible to transmit the drive equally to both ends of the paddle wheel shaft, that is, to apply equal amounts of driving torque thereto. In the case of the sprocket chain drive, there is apt to be a slight difference in the length of the chains when new and the chains and sprockets will wear unevenly and

one chain will have a tendency to stretch more than the other in use, or the bearings may wear unevenly. The result is that in time one chain and its sprockets will be doing practically all the work of driving the paddle wheel. This lowers the efficiency of the driving connections between the motor and paddle wheel, and produces such unequal strains in the driving connections as to cause frequent breakage of the overloaded chain and sprockets. In the case of the gear drive, there is a large number of gear teeth which are subjected to constant wear, so that more play soon develops in the gear drive at one side of the boat than in that of the other side thereof, or the bearings may wear unevenly. The result is the same as in the sprocket chain drive, that is, the gearing at the opposite sides of the boat will soon be transmitting the drive from the motor to the paddle wheel shaft unequally.

By the present invention, I overcome the

above difficulty by forming the cross shaft in sections and driving the same through differential gearing. This form of drive permits a relative movement between the sections of the cross shaft to take up any slack in the driving connections at the opposite sides of the boat and enables such driving connections to apply equal amounts of driving torque to the opposite ends of the paddle wheel shaft. I have also provided novel means for housing and lubricating the differential gearing and supporting the bearings for the adjacent ends of the propeller shaft and cross shaft.

In the accompanying drawings, I have illustrated my invention in connection with a boat having sprocket chain driving connections between the motor and paddle wheel shaft.

In the drawings:—

Figure 1 is a plan view of a boat having my invention applied thereto;

Figure 2 is a side elevation of the boat;

Figure 3 is a plan view of the paddle wheel and the driving connections between the same and the propeller shaft;

Figure 4 is a detail sectional view of the differential gearing;

Figure 5 is a plan view of the housing for the differential gearing;

Figure 6 is a section on the line VI—VI of Figure 5, and

Figure 7 is a section on the line VII—VII of Figure 5.

The reference numeral 2 designates the hull of a tow boat having a paddle wheel 3 at the stern thereof for propelling the same. The paddle wheel is mounted on a paddle wheel shaft 4, the end portions of which are journaled in bearings 5 mounted on the sides of the boat. Fixed to the ends of the paddle wheel shaft are driving sprockets 6. Extending transversely of the boat and parallel to the paddle wheel shaft is a cross shaft 7 formed in two sections and having its outer end portions journaled in bearings 8. Fixed to the outer ends of the cross shaft are sprockets 9 and connecting the sprockets on the corresponding ends of the paddle wheel shaft and cross shaft are sprocket chains 10.

Extending longitudinally of the boat is a propeller shaft 11 adapted to be driven by a motor 12 or other form of power unit. The propeller shaft is operatively connected to the cross shaft through differential gear-

ing. The differential gearing is housed in a casing 13, shown in detail in Figures 5, 6 and 7. The rear end portion of the propeller shaft is journaled in a bearing 14 mounted on the casing and the inner end portions of the sections of the cross shaft are journaled in bearings 15 also mounted on the casing. Fixed to the end of the propeller shaft within the casing is a bevel pinion 16 which meshes with a bevel rim gear 17 carried by a gear disk 18, the hub portion 19 of which is journaled on the inner end portions of the sections of the cross shaft 7. The gear disk 18 carries two diametrically opposite differential bevel pinions 20 rotatably mounted on pins 21 extending into openings 22 in the hub 19. These pins are held in position by the rim gear 17 which is bolted to the disk 18. The differential pinions 20 mesh with differential gears 23 fixed to the inner ends of the sections of the cross shaft.

It will be apparent that the differential gearing between the propeller shaft 11 and the cross shaft 7 provides a positive driving connection between the propeller shaft and the cross shaft and at the same time enables the sections of the cross shaft to have the necessary relative rotation for maintaining equal amounts of tension in the two sprocket chains 10. It will also be apparent that if gear trains were substituted for the sprocket chains and driving sprockets at the sides of the boat, the differential gearing in the driving connection between the propeller shaft and cross shaft would enable the drive to be transmitted equally through such gear trains.

In case one of the sprocket chains or some of the teeth of a driving sprocket or a cross-shaft section should break, it would be desirable to couple the gear disk 18 and the bevel gears 23 rigidly together so as to revolve as a unit. To that end, referring to Figure 4, the hub 19 of the gear disk 18 has a hole 24 extending therethrough which is adapted to be aligned with similar holes 25 in the bevel gears 23. A bolt may be passed through these aligned holes to couple the parts together.

The gearing casing 13 has angles 26 and 27 secured to its sides adjacent the upper edges thereof and supported on the horizontal flanges of these angles is a top plate 28 to which the bearings 14 and 15 are bolted. The casing is provided with a detachable cover 29, the lower edge portion 30 of which is adapted to make a snug sliding fit with the edges of a rectangular opening cut in said top plate. This cover has an angle 31 secured to its outer surface adjacent its lower edge portion. This angle is adapted to engage the plate 28, whereby the cover is supported on the plate. The cover is provided with suitable recesses 32

in its sides to receive the bearings 14 and 15, the edges of these recesses making a snug fit around the bearings. Angles 33 are secured to the faces of the cover adjacent the edges of the recesses 32, these angles being shaped to fit the bearings. The cover may be readily removed from the casing by simply lifting it out of engagement with the plate 28 and the bearings 14 and 15. The end portion of the plate 28 which supports the bearing 14 is additionally supported by an angle 34 and a bracket 35.

While I have illustrated my invention in connection with a sprocket chain drive between the cross shaft and paddle wheel shaft, it will be perfectly apparent that the invention is equally applicable to constructions in which there is a gear drive at each side of the boat between the cross shaft and paddle wheel shaft.

I claim—

1. In a boat, a paddle wheel shaft, a power unit, and driving connections between the ends of said shaft and said power unit including differential gearing, substantially as described.

2. In a boat, a paddle wheel shaft extending transversely thereof, a cross shaft extending parallel to the paddle wheel shaft, driving connections at the sides of the boat between the corresponding ends of said shafts, a power unit for driving said cross shaft, and differential gearing in the driving connection between said power unit and cross shaft, substantially as described.

3. In a boat, a paddle wheel shaft extending transversely thereof, a cross shaft formed in two sections, driving connections at the sides of the boat between the corresponding ends of said shafts, a propeller shaft, and differential gearing mounted on said propeller shaft and on the inner ends of the sections of the cross shaft, substantially as described.

4. In a boat, a paddle wheel shaft, a cross shaft formed in two sections, driving connections at the sides of the boat between the corresponding ends of said shafts, a propeller shaft, differential gearing mounted on said propeller shaft and on the inner ends of the sections of the cross shaft, and means for coupling the portion of said differential gearing mounted on the cross shaft together to revolve as a unit, substantially as described.

5. In a boat, a paddle wheel shaft extending transversely thereof and having driving sprockets mounted on the ends thereof, a cross shaft extending parallel to the paddle wheel shaft and having driving sprockets mounted on the ends thereof, sprocket chains engaging the sprockets on the corresponding ends of said shafts, and means including differential gearing for driving said cross shaft, substantially as described.

6. In a boat, a paddle wheel shaft extending transversely thereof and having driving sprockets mounted on the ends thereof, a cross shaft extending parallel to the paddle wheel shaft and having driving sprockets mounted on the ends thereof, sprocket chains engaging the sprockets on the corresponding ends of said shafts, a propeller shaft, and differential gearing connecting the propeller shafts with the cross shaft, substantially as described. 50
- 5 7. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, differential gearing mounted on said propeller shaft and on the inner ends of said sections, substantially as described. 55
- 15 8. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, and differential gearing mounted on said propeller shaft and on the inner ends of said sections, substantially as described. 60
- 20 9. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, differential gearing mounted on said propeller shaft and on the inner ends of said sections, and a casing enclosing said differential gearing, substantially as described. 65
- 25 10. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, differential gearing mounted on said propeller shaft and on the inner ends of said sections, a casing for said gearing having a top plate provided with an opening therein, a cover for said casing, the lower end portion of which has a sliding fit with the edges of said opening, and means carried by said cover adjacent said lower end portion for engaging said top plate and limiting the downward movement of said cover, substantially as described. 70
- 30 11. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, differential gearing mounted on said propeller shaft and on the inner ends of said sections, a casing for said gearing having a top plate provided with an opening therein, bearings for the propeller shaft and the sections of the cross shaft mounted on said top plate, and a cover for said casing, the lower end portion of which has a sliding fit with the edges of said opening, said cover having recesses in its faces to receive said bearings, substantially as described. 75
- 35 40 45 50 55 60 65 70 75 80 85 90 95
9. In a boat, a paddle wheel shaft extending transversely thereof and having driving sprockets mounted on the ends thereof, a cross shaft extending parallel to the paddle wheel shaft and formed in two sections, driving sprockets mounted on the outer ends of said sections, sprocket chains engaging the sprockets on the corresponding ends of the paddle wheel shaft and cross shaft, a propeller shaft, differential gearing mounted on said propeller shaft and on the inner ends of said sections, and a casing enclosing said differential gearing, substantially as described.
- In testimony whereof I have hereunto set my hand.
- FRANK R. DRAVO.
